UNITED STATES PATENT OFFICE.

JENNIE REDDEN HOLDEN, OF CAMBRIDGE, MASSACHUSETTS.

DESIGN FOR A BOOK-RACK.

49,147.

Specification for Design.

Patented June 6, 1916.

Application filed October 2, 1914. Serial No. 864,572. Term of patent 7 years.

To all whom it may concern:

Be it known that I, JENNIE REDDEN HOLDEN, of Cambridge, in the county of Middlesex and State of Massachusetts, have invented a certain new, original, and ornamental Design for a Book-Rack, of which the following is a specification.

The design is a flat shelf or base having at each end thereof an upright made in the shape of the bridge of a double-bass viol or similar stringed instrument. Parts of the strings of such instruments are employed as part of the design, one end of each string being fastened to the end of the base of the rack, carried over the bridge and fastened on

the inside, to represent the strings and bridge of such an instrument.

The drawing which accompanies this specification and forms part hereof shows a book-stand made according to my design.

I claim:

The ornamental design for a book-rack, as shown and described.

In testimony whereof I have affixed my signature, in presence of two witnesses.

JENNIE REDDEN HOLDEN.

Witnesses:

HELEN M. DEARBORN,
FRANK SHURTLEFF.
